CLAIM

The ornamental design for a container cap, as shown and described.

DESCRIPTION

FIG. 1 is a top, front, and right side perspective view of a container cap showing our new design;

FIG. 2 is an exploded perspective view of our new design shown with the container cap in an open position;

FIG. 3 is a front view of the container cap;

FIG. 4 is a right side view of the container cap;

FIG. 5 is a top view of the container cap; and,

FIG. 6 is a bottom view of the container cap.

The broken lines shown in the drawings represent environmental structure in FIGS. 1-6 that form no part of the claimed design. The dot-dash-dot lines shown in FIGS. 1-5 represent the boundary of the claim.
